COMBINED COUPLING AND RELEASING DEVICE

Henry M. Davis, Portsmouth, Va.

Application November 20, 1934, Serial No. 753,930

2 Claims. (Cl. 9—23)

This invention relates to a combined coupling and releasing device for connecting and releasing an object to and from an elevating and lowering means therefor.

The invention is designed primarily for use in connection with life boats, but it is to be understood that it may be employed in any connection for which it is found applicable, and the invention has for its object to provide, in a manner as hereinafter set forth, a device of the class referred to for connection to the ends of a life boat and by means of which the boat may be securely suspended from the davits of a vessel and automatically released when lowered to a position to contact with the water thus permitting the boat to immediately get away from the side of the vessel without delay and prevent damage thereto by pounding which otherwise would be the case in rough weather when delay is created in releasing the boat from its fastenings.

Further objects of the invention are to provide, in a manner as hereinafter set forth, a combined coupling and releasing device for the purpose referred to which is simple in its construction and arrangement, strong, durable, compact, thoroughly efficient in its use, automatically performing its releasing function, readily installed and comparatively inexpensive to manufacture.

To the above ends essentially and to others which may hereinafter appear, the invention consists of such parts and such combination of parts which fall within the scope of the invention as claimed.

In the drawing:

Figure 1 is a side elevation of the device in locked position and attached to an elevating and lowering means.

Figure 2 is a vertical sectional view of the device in locked position.

Figure 3 is an elevation looking towards the front of the device and released, and

Figure 4 is a side elevation of the device installed with respect to a life-boat, an elevating and lowering means thereof and a davit acting as a suspension for said means.

In the drawing 1 indicates one end of a life boat, 2 a davit, 3 an upper block carrying a pulley, 4 a lower block carrying a pulley and a depending shackle 5 of loop form and 6 an elevating and lowering cable travelling over the pulley in the upper block and around the lower portion of the pulley in the lower block. The block 3 is suspended from the upper end of the davit 2. One end of cable 6 is fixedly secured, as at 7, to the upper block 3. The cable 6 is ar-

ranged relatively to the blocks 3, 4 to provide an outer and an inner stretch 8, 9 respectively. It is the upper end of the stretch 9 which is secured, as at 7, to block 3.

The device includes a rectangular support 10 which, when the device is installed, is secured in an upstanding position to the upper portion of the inner face of boat end 1. In this connection attention is directed to Figure 4. The inner face of support 10 is formed with integral transversely extending parallel spaced ribs 11 constituting reinforcements for the support, as well as spacing means for the latter when it is secured to boat end 1. In proximity to each end and centrally of support 10 it is formed with the openings 12, 13 and 14 for the passage of holdfast means, not shown, for anchoring the device in position. The openings 12, 13 and 14 are disposed at the longitudinal median of the support. The latter has formed integral with its outer face, between the openings 12, 13, a pair of spaced parallel apertured upper lugs 15 which have their outer side faces flush with the side edges of support 10. Formed integral with the outer face of support 10, between the openings 13, 14 is a pair of spaced parallel apertured lower lugs 16 which are spaced from the lugs 15 and have their outer side faces flush with the side edges of support 10.

The device includes a counterweighted keeper 17, a holder 18 in which the keeper 17 is to engage, an automatically releasable primary latch 19 for detachably securing keeper 17 and holder 18 together when the boat is to be lowered from suspended position, and a manually operated auxiliary latch 20 for detachably connecting keeper 17 and holder 18 together when the boat is to be elevated to suspended position. The keeper 17 is of substantially inverted L-shaped contour and includes a horizontally disposed curved upper arm 21 and a vertically disposed lower arm 22 merging into the bottom edge of arm 21 outwardly adjacent to the inner end of the latter. The arm 21 has its top edge 23 in proximity to its outer end 24 formed with a transverse groove 25. The arm 21 is apertured, as at 26 in proximity to its inner end. The arm 22 has a reduced upper end portion 27 and is counterweighted at its lower end, as at 28. The inner end of arm 21 is positioned between the lugs 15 and extending through the apertures of said lugs 15 and aperture 26 of arm 21 is a headed bolt 29 upon which keeper 17 is pivoted. The bolt 29 carries a securing nut 30. 55

The counterweighted arm 22 tends to maintain the arm 21 in the full line position shown in Figure 3. The arm 21 in proximity to its outer end is formed with an inclined opening 31 which 5 extends from the bottom edge thereof and communicates with groove 25 at the base of the latter. The inclination of opening 31 is outwardly from its lower end.

The holder 18 comprises a loop 32 which 10 merges at its inner end into a neck 33 which extends from the outer or reduced end of an enlarged substantially triangular shaped body 34 having a semi-circular extension 35 positioned at one side of the inner or enlarged end of said body 34. The latter provides a counterweighting means for holder 18. The holder 18, at its enlarged end is formed with an aperture 36 which aligns with the transverse center of the extension 35. The latter and a part of the enlarged end 20 of holder 18 is positioned between the lugs 16. Extending through the apertures in lugs 16 and the aperture 36 in body 34 is a headed bolt 37 upon which holder 18 is pivoted. The bolt 37 carries a securing nut 38. That part of the 25 enlarged end of holder 18, not provided with the extension 35 constitutes an abutment for engaging support 10 to limit the lowering movement of holder 18 when the latter is in its inactive or non-holding position. When holder 18 is active 30 it is disposed at an upward outward inclination with respect to the front of support 10, and has the loop 32 thereof encompassing the outer end of arm 21 and with the upper end of the loop 32 seated in groove 25. The upper end of loop 32 has an inclined opening 39 registering with opening 31 in arm 21. The purpose of 35 openings 31 and 39 will be presently referred to.

The automatically operable primary latch 19 comprises a flexible pull member 40 which is 40 adapted to have one end secured to the stretch 9 of cable 6, as at 41, and its other end permanently secured to one end of a latching member 42, as at 43. The member 42 is in the form of 45 a pin, having an eye 44 at its upper end for connection to pull member 40.

The manually operated latch 20 is in the form 50 of a flexible carrying member 45, anchored at one end, as at 46, to the holder 18 and at its other end to one end of a latching member 47, as at 48. The member 47 is of the same form as member 42.

The latching member 42 is to extend through 55 the aligning openings 31, 39 when the boat is suspended from davit 2. The weight of the boat, when the latter is suspended, will maintain keeper 17 in interengagement with holder 18. The member 42, when extended through openings 31, 39, will prevent separation of the keeper and holder, due to any action of the vessel when 60 the boat is suspended or when being lowered. When the boat is lowered from davit 2, the stretch 9 will act to extend member 40 and carry the latter therewith. When the boat reaches 65 the water the weight thereof on the keeper 17 will be relieved, at which time the member 40 will be fully extended by stretch 9 and pulled upwardly therewith whereby the latching mem-

ber 42 will be shifted clear of openings 31, 39. At this point the arm 22 will provide for keeper 17 shifting on its pivot to the full line position, Figure 3, releasing holder 18 which will assume the full line position, Figure 3. On the separation of keeper 17 and holder 18 the keeper 17 will be moved to the dotted line position, Figure 3, whereby shackle 5 will slide off of keeper 17 releasing the boat from block 4. The release of keeper 17 relative to holder 18 is automatic and 10 the release of the device from the shackle 5 is also automatic.

After the release of the device from shackle 5, and it is desired to suspend the boat from davit 2, the keeper 17 is extended through the loop of 15 holder 18 and latching member 47, passed through openings 31, 39 whereby keeper 17 and holder 18 are connected together with the former supported from shackle 5. The boat is then elevated to its suspended position with respect to davit 2. The 20 weight of the boat on keeper 17 maintains the latter in interengaging position with respect to holder 18. After the boat has been elevated to the desired extent the latching member 47 is 25 removed and latching member 42 installed.

What I claim is:

1. A combined coupling and releasing device for the purpose set forth, comprising an inverted L-shaped keeper formed of a horizontally disposed upper arm pivoted adjacent its inner end and a counterweighted pendant lower arm, said upper arm being formed with a groove in proximity to its outer end and an opening extending from the base of the wall of the groove to the lower face of such arm, a holder formed with an offset pivoted part at its inner end and a counterweight adjacent the pivot for said offset part, said holder having a loop at its outer end and an opening in the outer end wall of the loop for registry with said other opening, an automatically releasing latching means extending through said openings when the openings register for detachably connecting the keeper and holder together.

2. In a combined coupling and releasing means, 45 an upstanding support, superposed pairs of spaced lugs on one face of said support, an inverted L-shaped keeper formed of an upper curved horizontal arm having a groove in proximity to its outer end and a pendant arm merging into said upper arm outwardly adjacent the inner end of the latter and having a counterweight at its lower end, said upper arm being pivoted adjacent its inner end to the lugs of the upper pair of lugs, a holder having a counterweight and an offset at its inner portion, said offset being pivotally connected to the lugs of the lower pair of lugs, said holder being formed at the outer end with a loop for the passage of 50 said upper arm, the outer end wall of said loop for seating in said groove whereby said upper arm will be held in abutting engagement with the holder when an upstanding pull is upon said upper arm, and an automatically releasable latching means for the outer ends of said upper arm 55 and holder.

HENRY M. DAVIS.
